UNITED STATES PATENT OFFICE.

ISAAC SHERCK, OF FREMONT, OHIO, ASSIGNOR OF SIX-EIGHTHS TO W. F. JOBBINS, OF NEW YORK, AND GEO. E. RAYMOND, OF BROOKLYN, N. Y.

TURBINE WATER-WHEEL.

SPECIFICATION forming part of Letters Patent No. 295,590, dated March 25, 1884.

Application filed February 6, 1883. (No model.)

To all whom it may concern:

Be it known that I, ISAAC SHERCK, of Fremont, in the county of Sandusky and State of Ohio, have invented certain new and useful Improvements in Turbine Water-Wheels; and I do hereby declare the following to be a full, clear, and exact description of the invention, such as will enable others skilled in the art to which it pertains to make and use the same.

10 My invention relates to an improvement in turbine water-wheels, and more particularly to that class thereof in which the water is admitted to the wheel through the periphery of a chute-ring surrounding it; the object of the invention being to provide a wheel of the character designated with an improved ring-gate.

15 A further object of the invention is to provide a wheel with a ring-gate arranged so as to be relieved within and without from water-pressure.

20 A further object of my invention is to provide improved means for mounting a ring-gate within a wheel whereby the resistance of friction is reduced to the minimum, the slight wear falling on the gate being so compensated for that the efficiency thereof is unaffected.

25 A further object of my invention is to provide means for maintaining the inner casing and the chute-ring in their appropriate positions, and preventing them from interfering with the action of the ring-gate, which is interposed between them, such devices serving also the secondary function of excluding sand from the gate.

30 35 A further object of my invention is to provide a wheel with a gate adapted to be carried through the whole range of its adjustment without changing the angle at which the water is impacted on the wheel. With these 40 several objects in view, my invention consists in certain details of construction and combinations of parts, as will be hereinafter described, and pointed out in the claims.

In the accompanying drawings, Figure 1 is 45 a view in perspective of a turbine wheel constructed in accordance with my invention. Fig. 2 is a view thereof in vertical cross-section. Fig. 3 is a view in perspective, embracing the inner casing, the bed, the crown-plate, 50 and the sleeve. Fig. 4 is a view of the chute-ring. Fig. 5 is a view of the ring-gate. Fig.

6 is a view of the guard-ring; and Fig. 7 is a view of the wheel in horizontal cross-section.

The cylindrical casing A, within which the wheel is located, rises centrally from the bed B, 55 the said parts being preferably cast integral. If desired, however, they may be made separate and secured together. The casing is provided with a series of apertures, C, the rear side walls, D, of which are beveled, while 60 their forward side walls, D', are curved. The object in curving the walls D' will be set forth hereinafter. The contour of these side walls is best shown in Fig. 7 of the drawings, in which the arrow indicates the direction in 65 which the wheel rotates.

The crown-plate E is removably secured to the upper edge of the casing A by bolts or equivalent means. In virtue of this construction the plate may be removed, leaving the 70 wheel exposed and permitting it to be removed or repaired without disturbing the parts located without the casing.

The chute-ring F is provided with a series of 75 apertures, G, having beveled side walls and corresponding in number and position to the apertures C in the casing. The ring is further provided with an upper bearing-ring, H, and a lower bearing-ring, I, the said bearing-rings being downwardly inclined in the same plane 80 for the purpose of elevating the water a little before its impact on the buckets of the wheel. Wings J located between the rings H and I are designed to deflect the water into the apertures G aforesaid. 85

The horizontal extension K of the bed B is provided with an annular recess, L, and with a shoulder, M, the lower face of the ring I being suitably cut away to fit down upon the said extension to which it is rigidly secured by 90 screws or equivalent devices. By fitting the said parts together, as above described, the displacement of the chute-ring is prevented.

The inner edge of the guard-ring N is adapted to fit closely around the upper portion of the 95 casing A, while its outer edge is provided with a depending flange, O, arranged to fit in an annular recess, P, formed in the outer edge of the ring H, to which the ring is attached by screws or equivalent devices. In virtue of 100 this construction and arrangement of parts, the guard-ring is made to form an additional safe-

guard against the displacement of the chute-ring. The guard-ring is further provided with two segmental slots, Q, opening into the space R, located between its upper face and the upper face of the ring H, and occupied for the most part by the flange U of the gate-ring U'. The bent ends S of the arms T of the frame-work V extend into and play in the said slots, the said ends of the arms being attached to the flange of the ring-gate.

The frame-work V, which is provided with a rack, X, is fitted over and arranged to move on the sleeve W as a pivotal center. A pinion, Y, journaled in the frame Z, secured to the crown-plate E, meshes with the rack X and actuates the frame-work and the ring-gate. Caps A', adapted to cover the slots Q in the guard-ring, are designed to prevent sand and other abrasive substances suspended in the water from entering the spaces R and B', the latter being the space between the casing and chute-ring in which the ring-gate is located. The said caps are provided with apertures C' to receive the ends of the arms T. As the frame-work is moved from side to side, the ends of the arms play in the slots Q, the caps being moved over the surfaces of the guard-ring without, however, exposing the slots.

The ring-gate U', which is located in the space B', before referred to, is provided with a series of apertures, E', corresponding in number and position with the apertures C and G of the casing A and chute-ring F, respectively. The flange U of the ring-gate has bearing upon the ring H of the chute-ring, as shown. Inasmuch as the ring-gate is interposed between the inner casing, A, and the chute-ring F, it is practically relieved of all water-pressure, and as there is no pressure of water upon its flange U, the force to be overcome in operating it is chiefly represented by the friction of the said flange upon the bearing-ring H. This friction being very slight, the parts are in a great measure preserved from wear, but all wear, however inconsiderable, is compensated for by leaving a space, F', between the lower edge of the gate-ring and the bed, so that as the flange U wears away the ring-gate is permitted to descend and take up the wear. The form of ring-gate which I have shown is the one which I prefer to employ; but it is evident that so far as the form and position of the flange U are concerned that the gate may be modified.

The chute-ring and the inner casing are rigidly secured together in such relative positions that the curved walls of the apertures of the latter will be a little in advance of the beveled walls of the apertures of the former. In virtue of this relation and of the curved contour of the forward side walls, D', of the apertures of the casing, the water in entering the wheel will not be retarded by contact with the inner casing, whether the ring-gate is adjusted to admit the full head of water to the wheel or only a part thereof.

It should be observed, that although the

ring-gate is rotated in regulating the amount of water supplied to the wheel, the angle at which the water is impacted on the bucket's is not changed, thus insuring a uniform and steady action of the wheel. 70

I would have it understood that I do not limit myself to the exact construction shown and described, but I hold myself at liberty to 75 make such changes and alterations as may be considered to fairly fall within the spirit and scope of my invention.

Having fully described my invention, what I claim as new, and desire to secure by Letters 80 Patent, is—

1. In a turbine water-wheel, the combination, with the inner casing having a series of apertures whose rear walls are beveled and whose forward walls are curved, of a rigid 85 chute-ring surrounding it, having apertures provided with deflecting-wings, and a gate interposed between the casing and the chute, consisting of a band or ring of metal arranged to be rotated, and provided with apertures 90 corresponding in number and position with those of the casing and chute, substantially as set forth.

2. In a turbine water-wheel, the combination, with an inner casing, of a chute-ring surrounding the casing, a ring-gate interposed 95 between the casing and chute, and a ring-guard located above the gate.

3. In a turbine water-wheel, the combination, with an inner casing, of a chute-ring surrounding the casing, a ring-gate interposed 100 between the casing and chute, and a ring-guard located above the gate, and arranged to prevent the displacement of the chute-ring.

4. In a turbine water-wheel, the combination, with an inner casing, of a chute-ring surrounding the casing, a ring-gate interposed between the casing and chute, and a ring-guard located above the gate, and provided with slots 105 to permit the gate to be attached to the mechanism which actuates it, substantially as and for the purpose set forth.

5. In a turbine water-wheel, the combination, with an inner casing, of a chute-ring surrounding the casing, of a ring-gate interposed 115 between the casing and chute, and a guard-ring located above the gate, and arranged to inclose a space above the upper ring of the chute.

6. In a turbine water-wheel, the combination, with an inner casing, of a chute-ring surrounding the casing, a ring-gate interposed 120 between the casing and chute, and provided with a flange having bearing upon the upper ring of the chute.

7. In a turbine water-wheel, the combination, with an inner casing, of a chute-ring surrounding the casing, a ring-gate interposed between the casing and chute, and provided with a flange having bearing upon the upper ring of the chute, and a ring-guard located 125 above the gate, and adapted to inclose and protect the flange of the gate.

8. In a turbine water-wheel, the combination, with the inner casing having a series of

apertures whose rear walls are beveled and whose forward walls are curved, of a chute-ring surrounding it, and having apertures provided with deflecting-wings, and rigidly secured to the bed of the wheel, and a gate interposed between said casing and chute, consisting of a band or ring of metal provided with apertures corresponding in number and position with those in the casing and chute, and devices, substantially as shown, for rotating the gate, as and for the purpose set forth.

9. In a turbine water-wheel, the combination, with an inner casing, of a chute-ring enclosing the casing and a ring-gate interposed

between said casing and chute-ring, the said casing-ring and gate being provided with registering-apertures, the apertures of the casing, the forward side walls of which are curved, being set in advance of the apertures of the chute-ring, substantially as and for the purpose set forth.

In testimony whereof I have signed this specification in the presence of two subscribing witnesses.

ISAAC SHERCK.
